8 Claims. (Cl. 250—49.5)

The invention relates to an electrostatic immersion objective, as required for example in electron emission microscopes.

The state of the art and an embodiment of the invention will now be described with reference to the accompanying drawings, in which:

FIGS. 1, 2 and 3 show known forms of electrostatic immersion objectives;

FIG. 4 shows an electrostatic immersion objective constructed in accordance with the invention;

FIG. 5 shows the electrostatic immersion objective of FIG. 4 connected to a source of operating potentials;

FIG. 6 shows an enlarged cross-section of an intermediate electrode according to one embodiment of the invention; and

FIG. 7 shows an enlarged cross-section of an intermediate electrode and cathode according to another embodiment of the invention.

In a known electrostatic immersion objective shown in FIG. 1, the object consists of a cathode K, a control electrode S and an anode A. The cathode K is at a strongly negative potential with respect to the anode; the control electrode S is at a potential which lies in the region of the cathode potential. The electrons emitted from the cathode K under some influence (temperature, bombarding with particles or electromagnetic waves) are accelerated by the electrostatic field between the anode A and cathode K and pass through the hole in the anode A into the image space. Because of the controlling action of the control electrode S, the arrangement as a whole acts on the electrons like a converging lens, so that in the image space below the anode A an image of the surface of the cathode K is produced by the emitted electrons. The object of the image is therefore the surface of the cathode K.

The resolving power of such an arrangement is given by the formula

$$\delta = k \cdot \frac{\epsilon}{E}$$

δ denotes the resolving power, ϵ is the mean velocity of the emitted electrons, E is the field intensity in front of the cathode K and k is a numerical factor depending on the geometry of the objective and the nature of the object.

The velocity distribution and hence the value cannot be influenced by the form of the objective. To obtain good resolution, therefore, the factors E and k have to be influenced. The field intensity E in front of the cathode K should be as high as possible, while the factor k , which includes the image forming properties of the objective, should be made as small as possible. Good image forming properties mean small lens errors.

The immersion objective shown in FIG. 1 represents a compromise which does not create optimal conditions. The electrostatic field between the anode A and cathode K is heavily screened by the control electrode S. The smaller the hole in the control electrodes, the smaller is the penetration of the electrostatic field therethrough and the smaller the field intensity in front of the cathode K. If, however, the hole in the control electrodes is made

2

larger, the image forming properties of the objective deteriorate and the factor k increases.

An experiment has been carried out (A. Septier, These, Paris, 1954), to improve conditions by inserting a further electrode Z at anode potential between the control electrode S and cathode K. This gives the arrangement shown in FIG. 2: the anode A and the intermediate electrode Z are at the same potential, relative to which the cathode K and control electrode S are strongly negative biased. The purpose of the arrangement is to separate the two factors E and k and to influence each individually. In fact, the effective field in this arrangement is produced mainly between the cathode K and the intermediate electrode Z, while the three electrodes Z, S and A together form an electrostatic Einzel lens.

In such an arrangement the field intensity in front of the cathode K can now be influenced by altering the distance between the cathode K and the intermediate electrode Z without the properties of the Einzel lens being affected. Conversely, the properties of the Einzel lens can be altered without affecting the field intensity in front of the cathode. Thus it must be possible to improve the resolving power.

The experiment's result was negative; the resolving power could not be improved. Moreover, it was found that no reasonable images could be obtained by means of this arrangement because of unusually severe image distortions.

The new investigation which led to the present invention were started on the assumption that the principle of the immersion lens with four electrodes as shown in FIG. 2 was in itself suitable for improving the properties of an emission microscope. The intention was therefore to ascertain what additional conditions had to be fulfilled by an immersion objective consisting of four electrodes, and how far the negative result of the earlier experiments was caused by non-observance of these conditions.

According to the invention which resulted from these new investigations, there is contemplated an electrostatic immersion objective comprising a cathode, an intermediate electrode, a control electrode and an anode. The intermediate and control electrodes and the anode each having a bore or opening. The thickness of the intermediate electrode which lies between the cathode and the control electrode is, at least in the vicinity of its bore in it, at most a fifth of the distance between cathode and intermediate electrode. And the diameter of the bore in the intermediate electrode is at most a fifth of the distance between cathode and intermediate electrode.

The possibility of incorporating an intermediate electrode Z in an immersion objective with three electrodes in such a way that it improves the properties of the objective therefore depends primarily on the form of this intermediate electrode itself. On the basis of the investigations the decisive factor for the image quality is the homogeneity of the electrostatic field along the electron beam between the cathode K and the entry in the Einzel lens. Evidently this fact was not taken into consideration in the earlier experiments and homogeneity of the electrostatic field was only demanded for the space nearest the cathode K. The thickness of the intermediate electrode Z has no substantial influence on this limited space. Similarly, no such rigorous requirements have to be laid down for the bore diameter. The construction of the immersion lens used for the earlier experiments follows this conception. Such a construction is shown in FIG. 3. The dimensions are as follows: the distance a between cathode K and intermediate electrode Z is from 1 to 2 mm. (millimeters); the thickness z of the intermediate electrode Z measures 2 mm. (millimeters); the diameter D_z of the bore in the intermediate electrode Z is 1 mm.

(millimeter). With these dimensions, it is true, suitable homogeneity of the electrostatic field can be expected in the immediate vicinity of the cathode K, but at a short distance from the cathode K the electrostatic field becomes severely non-homogeneous, particularly when $a = \frac{1}{2}z$. The electron beam does not enter the electrostatic field of the Einzel lens comprising intermediate electrode Z, control electrode S and anode A until it reaches the neighborhood of the lower edge of the intermediate electrode Z. In the long bore of the intermediate electrode Z only the penetration of the electrostatic field acts; there is, therefore, a long trajectory, in this bore, in a non-homogeneous field. Here arise the severe aberrations mentioned by Septier. The inferiority of this arrangement is also shown by the fact that images could only be obtained when the potential difference between the control electrode S and the cathode K was at least a tenth of that between the cathode K and the anode A. This initial potential difference, however, is detrimental to the properties of the Einzel lens, so that good resolution cannot be expected. The long bore in the intermediate electrode Z also causes reflections of electrons from the walls of the bore. These reflections make the image formation worse.

These drawbacks are avoided by means of the invention, an embodiment of which is shown in FIG. 4. The immersion objective consists of a cathode K, an intermediate electrode Z, a control electrode S and an anode A. The dimensions in this embodiment are as follows: the distance a is 3 mm. (millimeters); the thickness z of the intermediate electrode is 0.25 mm. (millimeter) in the middle, but it increases outwardly for greater strength; the diameter of the bore D_z in the intermediate electrode is 0.3 mm. (millimeter). The electrostatic field between the cathode K and intermediate electrode Z remains homogeneous in this arrangement until near the bore, and the necessarily non-homogeneous part in and near the bore is kept very short as the beam immediately enters the field of the Einzel lens. The reflections from the walls of the bore are also reduced.

The characterizing feature of the embodiment described is that the thickness of the intermediate electrode Z is less than a tenth of the distance between cathode K and intermediate electrode Z and the diameter of the bore in the intermediate electrode Z is at most a tenth of the distance between cathode and intermediate electrode.

To reduce the reflections from the walls of the bore in the intermediate electrode Z still further, the edges B_e of the bore may be rounded as shown in FIG. 6.

Funnel-shaped bores B_f (FIG. 7) are particularly suitable, the narrow part of the bore preferably facing the cathode K.

By selecting the dimensions of the intermediate electrode Z and cathode K in accordance with the invention, conditions are created in which a homogeneous electrostatic field of great field intensity can be produced between the cathode K and the intermediate electrode Z without regard to the succeeding electrodes. Because of this the image brightness is increased on the one hand and the prerequisites for obtaining an image with good resolution are fulfilled on the other. This image has to be magnified by the Einzel lens. It is therefore essential for the good resolution to be retained as far as possible in the Einzel lens. For this reason a lens with the least possible aberrations should be chosen. Septier's experiments were with a thick Einzel lens as used for projection lenses low in distortion. These projection lenses are not suitable for use as objective lenses, however, because of their other lens errors. The objective shown in FIG. 4 therefore has a thin Einzel lens of the kind used as objective lenses in transmission microscopes. In this embodiment the intermediate electrode Z, the control electrode S and the anode A are so constructed that together they have the properties of a good electrostatic objective lens.

The small bore in the intermediate electrode Z normally, after manufacture and in use, shows certain deviations from rotational symmetry which make themselves visible in the image as astigmatism. Such errors in the image can be compensated by suitable transverse displacement or by inclination of the various electrodes towards each other. It is therefore an advantage if one or more electrodes can be adjusted while in use.

In the embodiment shown in FIG. 4, the field penetration through the bore in the intermediate electrode Z is very small. The control electrode S therefore really acts as the middle electrode of an Einzel lens and can be operated at a potential identical to or only little different from the cathode potential. A special feature of the preferred embodiment is therefore that the potential difference between the control electrode S and the cathode K is less than a tenth of the potential difference between the cathode K and anode A.

This potential difference is preferably made variable within the limits given; it then influences the focal length of the immersion objective and can be used for sharp-focussing the image. In one embodiment, therefore, a variable potential which is small compared with the cathode-anode potential difference is applied to the control electrode S to sharp-focus the image. This can be accomplished by connecting the moving arm W of potentiometer R to the control electrode S as shown in FIG. 5.

It is well known that in any immersion objective the best resolution can only be obtained if the rays of wide aperture are projected onto a screen. This screen B is also shown in FIG. 4. In the preferred embodiment, therefore, an aperture screen follows the anode A.

A lower limit is set on the dimensions of the bore in the intermediate electrode Z by the fact that this bore restricts the image size. If the minimum final magnification is set at 300 $\times$ and the image diameter at this magnification is set at 60 mm. (millimeters), an approximate lower limit for the bore diameter is

$$\frac{60}{300} = 0.2 \text{ mm.}$$

The selected dimension of 0.3 mm. (millimeter) is therefore quite allowable for this case. The size of the bore of the intermediate electrode Z is preferably chosen so that the bore acts in such a way as to restrict the image at the smallest final magnification used.

If the electrons are deflected after passing through the immersion objective by a device which deflects electrons more strongly than ions, for instance a magnetic deflection field, the negative ions which are otherwise masked as to intensity by the electrons stay behind in the beam. The immersion objective is then also suitable for taking ion-optical surface pictures. If all potentials applied to the immersion objective are subjected to polarity reversal, i.e. 55 the cathode and anode interchange, the objective is suitable for image formation with positive ions. The immersion objective of the invention may therefore be adapted to form images both with electrons and with ions.

What I claim is:

60 1. An electrostatic immersion objective comprising a cathode, an intermediate electrode, a control electrode, and an anode, said cathode, intermediate electrode, control electrode and anode being serially arranged in spaced relation in the aforesaid order, the intermediate and control electrodes and anode having aligned bores, said cathode and intermediate electrode having flat parallel surfaces which face one another and are spaced apart a determinable distance, said intermediate electrode having a thickness at said bore and a diameter of said bore related to the distance between the flat surfaces of the cathode and the intermediate electrode to provide a homogeneous field in the bore of the intermediate electrode, said diameter of the bore of the intermediate electrode being less than one-fifth of said distance between the flat surfaces of the cathode and the intermediate electrode while said thick-

ness of the intermediate electrode at said bore is less than one-fifth of the aforesaid distance.

2. The objective as claimed in claim 1, in which the thickness of said intermediate electrode is, at least in the region of its bore, a tenth of the distance between said cathode and said intermediate electrode, and the diameter of the bore in said intermediate electrode is substantially a tenth of the distance between said cathode and said intermediate electrode.

3. The objective as claimed in claim 1, in which the edges of the bore of said intermediate electrode are rounded.

4. An objective according to claim 1 wherein said bore in the intermediate electrode has a funnel shape with a narrow portion facing the cathode.

5. The objective as claimed in claim 1 including means for maintaining a given potential difference between said anode and said cathode, means for maintaining said intermediate electrode at substantially the same potential as said anode, and means for maintaining said control electrode at substantially the same potential as said cathode.

6. The objective as claimed in claim 5 wherein the potential of said anode is greater than the potential of said cathode.

7. The objective as claimed in claim 1 including means for maintaining a given potential difference between said anode and said cathode, and means for applying a potential difference between said control electrode and said cathode having a magnitude which is less than a tenth of said given potential difference between said cathode and said anode.

8. The objective as claimed in claim 1 including an aperture screen disposed beyond said anode.
